UNITED STATES PATENT OFFICE

EARL J. W. RAGSDALE, OF NORRISTOWN, PENNSYLVANIA, ASSIGNOR TO EDWARD G. BUDD MANUFACTURING COMPANY, OF PHILADELPHIA, PENNSYLVANIA, A CORPORATION OF PENNSYLVANIA

DESIGN FOR A MOTOR VEHICLE

Application filed May 16, 1932. Serial No. 43,824. Term of patent 14 years.

To all whom it may concern:

Be it known that I, EARL J. W. RAGSDALE, a citizen of the United States, residing at Norristown, in the county of Montgomery and State of Pennsylvania, have invented a new, original, and ornamental Design for a Motor Vehicle, of which the following is a specification, reference being had to the accompanying drawings, which form a part hereof.

Fig. 1 is a perspective view of a vehicle showing my new design as seen from the side and to the front;

Fig. 2 is a side elevation view thereof;

Fig. 3 is a plan view thereof;

Fig. 4 is a perspective view from the rear and to one side;

Fig. 5 is a perspective view from the direct rear;

Fig. 6 is a perspective view from its direct front.

I claim:

The ornamental design for a motor vehicle substantially as shown.

Signed at Philadelphia, county of Philadelphia, State of Pennsylvania, this 14th day of May, 1932.

EARL J. W. RAGSDALE.
